ROLLER SKATE

James Edward Marshall, New Haven, Conn., assignor to Winchester Repeating Arms Company, New Haven, Conn., a corporation of Maryland

Application June 28, 1933, Serial No. 677,962

4 Claims. (Cl. 208—173)

This invention relates to roller skates and more particularly to a roller skate having improved adjusting means to fit the skate to the shoe of the skater.

5 In carrying out my invention I provide a skate comprising a heel plate and toe plate having a girder formed integrally with one of said plates, preferably the toe plate. The girder is provided with an elongated slot adopted to receive a bolt 10 carried by the heel plate to adjust the size of the skate. I further provide side flanges on the girder which may extend throughout a portion of the toe plate to stiffen it and produce a more rigid construction.

15 The girder flanges are provided with longitudinal ribs or grooves to increase the strength of the skate. By forming ribs on the flanges it is possible to employ lighter material in the construction of the skate and still obtain a rugged 20 construction.

In one form of the invention, the rear truck hangers are provided with inwardly extending lugs suitably spaced from the heel plate to form ledges on which the girder flanges rest. This 25 provides a more rigid construction than would be obtained if these ledges were omitted.

In another form of the invention the side walls of the truck hangers are provided with ribs which are received in the longitudinal grooves of the 30 girder flanges and form guides for the girder.

A further feature of the invention consists in providing indentations in the truck hangers whereby a more rigid construction is obtained and whereby the elastic cushion generally employed in skate constructions is rigidly clamped 35 in the truck hanger.

In the accompanying drawing I have shown several forms of the invention. In the drawing, Fig. 1 is a side elevation of one form of skate, 40 parts being shown in section;

Fig. 2 is a plan view thereof;

Fig. 3 is a transverse, vertical, sectional view on line 3—3 of Fig. 1;

Fig. 4 is a detailed view of the rear truck 45 hanger; and,

Fig. 5 is a transverse, vertical, sectional view (similar to Fig. 3) showing a modified form of the invention.

Referring to the drawing, the reference 50 numeral 1 designates a toe plate and 2 a heel plate of a skate. A girder 3 is formed integrally with one of the foot plates, preferably being formed integrally with the toe plate as shown. This girder is provided with a longitudinal slot 4. A bolt 5 is mounted in an opening in the heel

plate and is adapted to pass through the slot 4. A nut 6 is mounted on the bolt to permit the plates to be retained in any desired adjusted position.

The girder is provided with downwardly extending side flanges 7 which may be formed integrally with marginal flanges 8 extending throughout a portion of the toe plate. The flanges 7 are provided with longitudinal grooves 9 on their outer sides forming ribs on the inner side of these flanges. The longitudinal grooves 9 materially strengthen the girder and give support to the skater at a point where the skate is normally subjected to considerable strain. By providing these grooves and strengthening the 70 girder construction, I find that lighter material may be employed in the construction of the skate and at the same time obtain sufficient ruggedness for usual skate use.

A truck hanger is arranged on each of the 75 foot pieces of the skate. These truck hangers are essentially of the same construction and the same reference numerals will, therefore, be employed to designate the various parts. Each of the truck hangers consists of a pair of parallel side 80 plates 10. They are secured to the foot pieces by integral rivet lugs 11 carried on the upper surfaces of the side pieces and adapted to pass through slots in the foot pieces. After the rivet lugs are in position in the slots they are headed over in the usual manner to secure the truck 85 hangers in place. The side pieces are connected by a cross member 12 which is preferably arranged at an incline to the plane of the foot pieces and which is provided with front and rear flanges 13 and 14. The truck hanger cooperates 90 with a cradle member or axle support 15 which is of substantially the same size and arranged parallel thereto. This member is also provided with front and rear flanges 16 and 17 adapted to be 95 arranged adjacent the flanges 13 and 14 of the truck hanger. A rubber cushion member 18 is arranged in the space formed by the truck hanger and supporting member 15 and a cotter pin 19 is passed through the rubber pad and through aligned openings in the flanges 13, 14, 15 and 16. The supporting member 15 carries a sleeve 20 100 adapted to receive an axle 21 on which the rolls 22 are mounted.

In the form of the invention shown in Figs. 1 to 4 of the drawing the upper portions of the side plates are slightly offset as shown at 23 and are slightly spaced from the flanges of the girder 3. Beneath this offset portion the side plates are spaced from each other a distance substantially equal to the width of the girder as 110

shown in Fig. 3 of the drawing. The rear side plates are provided with lugs 24 struck inwardly from the body of the material forming ledges upon which the side flanges 7 of the girder are adapted to rest. These ledges are spaced from the top of the side plate a distance equal to the width of the flange 7 so that with the lower edge of the flange resting on the ledge the girder is retained in close contact with the bottom of 10 the heel plate.

In the form of the invention shown in Fig. 5 of the drawing the side plates 10 are not provided with the offset portions 23 but extend upwardly to the heel plate 2 at a distance from each other substantially equal to the width of the girder 3. They are provided with longitudinally extending grooves 25 on their outer faces adapted to form longitudinally extending ribs on their inner faces, which ribs are received in the grooves 9 of the 20 flanges of the girder. It will be apparent that this construction provides a guide for the girder and adds to the rigidity of the skate.

To further add to the rigidity of the skate and permit the use of lighter material in the construction of the skate without sacrificing necessary strength, I provide indentations 26 at the front and rear edges of the cross piece 12 which connects the side pieces 10 of the truck hanger. Similar indentations may be provided at the junction 30 of the side walls 10 and the cross piece 12. These indentations, which are preferably formed at the point where the end flanges 13 and 14 are joined to the body portion of the cross piece, not only add to the strength of the truck hanger but also more rigidly clamp the cushioning pad in position.

The toe piece is provided with the usual clamps 27 mounted on a suitable bracket on the bottom of the toe piece and adapted to be adjusted by a threaded rod 28 in the usual manner. Likewise, the heel piece is provided with the usual flanges 29 to which a skate strap (not shown) may be attached in any suitable manner. The toe plate may also be provided with ribs 30 formed in 45 the metal for the purpose of strengthening this member and thereby permit the use of lighter material.

It will be apparent from the foregoing description that I have provided a roller skate which 50 is made of a relatively small number of parts

and which is of simple construction and therefore relatively inexpensive to manufacture. At the same time the construction provides unusual ruggedness and therefore permits the use of light material in the manufacture of the skate.

I claim:

1. A roller skate comprising a toe plate, a heel plate, a girder carried by said toe plate, means for securing said girder to said heel plate in adjustable positions, side flanges formed on said girder, said flanges being provided with longitudinally extending grooves, truck hangers carried by said toe plate and said heel plate, said truck hangers having vertically arranged parallel side plates, and girder supporting means projecting inwardly from said side plates and adapted to receive the lower faces of said flanges.

2. A roller skate comprising a toe plate, a heel plate, a girder carried by said toe plate, means for securing said girder to said heel plate in adjustable positions, side flanges formed on said girder, said flanges being provided with longitudinally extending grooves, truck hangers carried by said toe plate and said heel plate, said truck hangers having vertically arranged parallel side plates spaced from each other a distance equal to the width of said girder, said side plates being provided with longitudinally extending ribs adapted to be received in the longitudinally extending grooves of said girder flanges to form a 105 guide for said girder.

3. A roller skate comprising a foot plate, a truck hanger secured to said foot plate, a cross member forming a part of said truck hanger and adapted to form a support for a cushioning pad, 110 said cross member being provided with indentations at its edges to strengthen said truck hanger.

4. In a roller skate, a truck hanger having a cross member, end flanges formed on said cross member, an axle support spaced from said cross member, said axle support being provided with flanges adjacent said first mentioned flanges, a cushioning pad arranged between said cross member and said axle support, said flanges being provided with aligned openings, and pivoting means arranged in said openings, said cross member being provided with indentations adjacent its ends.

JAMES EDWARD MARSHALL.

55

5. A roller skate comprising a toe plate, a heel plate, a girder carried by said toe plate, means for securing said girder to said heel plate in adjustable positions, side flanges formed on said girder, said flanges being provided with longitudinally extending grooves, truck hangers carried by said toe plate and said heel plate, said truck hangers having vertically arranged parallel side plates, and girder supporting means projecting inwardly from said side plates and adapted to receive the lower faces of said flanges.

60

6. A roller skate comprising a toe plate, a heel plate, a girder carried by said toe plate, means for securing said girder to said heel plate in adjustable positions, side flanges formed on said girder, said flanges being provided with longitudinally extending grooves, truck hangers carried by said toe plate and said heel plate, said truck hangers having vertically arranged parallel side plates spaced from each other a distance equal to the width of said girder, said side plates being provided with longitudinally extending ribs adapted to be received in the longitudinally extending grooves of said girder flanges to form a 105 guide for said girder.

65

7. A roller skate comprising a foot plate, a truck hanger secured to said foot plate, a cross member forming a part of said truck hanger and adapted to form a support for a cushioning pad, 110 said cross member being provided with indentations at its edges to strengthen said truck hanger.

80

8. In a roller skate, a truck hanger having a cross member, end flanges formed on said cross member, an axle support spaced from said cross member, said axle support being provided with flanges adjacent said first mentioned flanges, a cushioning pad arranged between said cross member and said axle support, said flanges being provided with aligned openings, and pivoting means arranged in said openings, said cross member being provided with indentations adjacent its ends.

70

9. A roller skate comprising a toe plate, a heel plate, a girder carried by said toe plate, means for securing said girder to said heel plate in adjustable positions, side flanges formed on said girder, said flanges being provided with longitudinally extending grooves, truck hangers carried by said toe plate and said heel plate, said truck hangers having vertically arranged parallel side plates, and girder supporting means projecting inwardly from said side plates and adapted to receive the lower faces of said flanges.

75

10. A roller skate comprising a foot plate, a truck hanger secured to said foot plate, a cross member forming a part of said truck hanger and adapted to form a support for a cushioning pad, 110 said cross member being provided with indentations at its edges to strengthen said truck hanger.
